UNITED STATES PATENT OFFICE

94,376

DESIGN FOR A SHOE

Marjorie Bancroft, Newton, Mass.

Application October 25, 1934, Serial No. 53,749

Term of patent 3½ years

To all whom it may concern:

Be it known that I, Marjorie Bancroft, a citizen of the United States, residing at Newton, in the county of Middlesex and Commonwealth of Massachusetts, have invented a new, original, and ornamental Design for a Shoe, of which the following is a specification, reference being had to the accompanying drawing, forming a part thereof, in which

Fig. 1 is a view in side elevation of a shoe showing my design; and

Fig. 2 is a plan view of the shoe.

The ornamental effect of my design resides in a rolled ornament located upon the forepart of

the shoe and extending from its point of attachment first forwardly above the surface of the forepart and then upwardly and rearwardly in smooth curve, and finally forwardly again toward the center of curvature of the ornament, the forward end of the ornament increasing in width and being flared outwardly at its front corners so that they extend symmetrically upon each side.

I claim:

The ornamental design for a shoe substantially as shown and described.

In testimony whereof, I have affixed my signature hereto.

MARJORIE BANCROFT.
